United States Patent Office

Des. 176,284
Patented Dec. 6, 1955

176,284

POCKET RADIO

Ralph E. Potter, Washington, D. C.

Application April 8, 1955, Serial No. 35,428

Term of patent 14 years

(Cl. D56—1)

Fig. 1.

Fig. 2.

Fig. 1 is a front perspective view of a pocket radio showing my new design;

Fig. 2 is a rear perspective view thereof.

I claim:

The ornamental design for a pocket radio, substantially as shown.
